UNITED STATES PATENT OFFICE.

LOUIS J. STERN, OF BOSTON, MASSACHUSETTS.

DESIGN FOR A WATER-COOLER.

49,939.

Specification for Design.

Patented Nov. 21, 1916.

Application filed May 26, 1916. Serial No. 100,161. Term of patent 14 years.

To all whom it may concern:

Be it known that I, LOUIS J. STERN, a citizen of the United States, residing at Boston, in the county of Suffolk and State of Massachusetts, have invented a new, original, and ornamental Design for Water-Coolers, of which the following is a specification, reference being had to the accompanying drawing, forming part thereof.

The figure is a perspective view of a water cooler, showing my new design.

I claim:

The ornamental design for a water cooler, as shown.

LOUIS J. STERN.

Witnesses:

H. B. DAVIS,
B. J. NOYES.
